UNITED STATES PATENT OFFICE.

JOHANN CARL GRÄBNER AND HENRI RUPERTI, OF KUPFERHAMMER,
NEAR BRACKWEDE, PRUSSIA, GERMANY.

CYLINDER AND PISTON MOTOR-ENGINE.

SPECIFICATION forming part of Letters Patent No. 425,172, dated April 8, 1890.

Application filed August 30, 1889. Serial No. 322,448. (No model.)

To all whom it may concern:

Be it known that we, JOHANN CARL GRÄBNER, a subject of the King of Bavaria, and HENRI RUPERTI, a subject of the Grand Duke of Mecklenburg, both residing at Kupferhammer, near Brackwede, Westphalia, Prussia, German Empire, have invented new and useful Improvements in Cylinder and Piston Motor-Engines, of which the following is a specification.

Our invention relates to motor-engines operated by steam, compressed air, or other expansive gases or vapors, and has particular reference to the construction shown in Figures 1 to 4 of the drawings in a prior application filed by us on the 21st day of February, 1889, Serial No. 300,790.

We shall in the following description speak of steam as the "motor fluid;" but it is to be understood that the improvements are equally applicable to other expansible gases or vapors under pressure.

Our present improvements relate to the appliances for admitting the steam to and exhausting the same from the cylinder.

Fig. 1 of the accompanying drawings is a longitudinal section of the engine-cylinder and piston and parts combined therewith, and Fig. 2 is a cross-section on line C'D in Fig. 1.

The appliances for admitting steam to the cylinder A consist, first, of the two piston-slides *h* *h'*, connected by the rods *c* *c'* with the air-buffer pistons *d* *d'*, and, secondly, of the steam-passages *a'*, *a''*, *b*, *m*, and *m'*.

The appliances for the exhaust consist of two piston-slides *i* and *i'*, connected together by a rod, which are actuated by steam passing through the passages *f''* and *f'''*. The piston-slides *i* and *i'* are connected by a rod with an air-buffer piston *d''*.

The piston-valves are preserved from concussion either by means of the air-buffer pistons *d* *d'* or by any other arrangement of buffers.

The action of the apparatus is as follows: Assuming the piston B to be in the position shown in Fig. 1—namely, at the end of the stroke to the left hand—then the steam-supply pipe *a* will be in communication through port *b*, hollow piston B, and existing opening between the edge 1 of the cylinder and edge

2 of the piston with the cylinder-space behind the piston. At the same time the piston-slide *h* will be pushed up into the position shown by the excess of steam-pressure on its under side (as the steam passing to its upper side through passage *a'* only acts on an annular surface,) thereby uncovering the passage *m*, so that steam will then also pass through this passage behind the piston, causing it to commence its stroke to the right. When during such motion the edge 2 passes over edge 1, the steam will not be entirely cut off, as this will only take place when the piston closes the passage *m*, and from this point the expansion will commence. In consequence of the resulting reduction of pressure, the full pressure exerted above the piston-slide *h* will now force it down again, closing the other end of passage *m*, and it will remain in this position until on the following stroke to the left of piston B the edge 2 again uncovers edge 1, when piston-slide *h* will be again forced upward. The same will take place with reference to piston-slide *h'* when, toward the end of the stroke to the right, the edge 3 of piston B passes edge 4 of the cylinder, thereby admitting steam in front of the piston both through the opening 3 4 and the passage *m'* and cushioning the piston at the end of its stroke. Steam will continue to be admitted until by the travel of the piston to the left the opening at 3 4 is closed, as also the passage *m'*, by the descent of the piston-slide *h'*, whereupon expansion will take place as before.

The exhaust is governed by the exhaust piston-slides *i* *i'*, connected by a rod. At the commencement of the stroke to the right of the piston B the passage *f'* is open, as shown, and the steam in front of the piston escapes through the exhaust-pipe *g*. As soon, however, as the edge 3 of the piston B reaches the opening of the passage *f'''*, steam will pass from the interior of the piston B through passage *f'''*, behind piston-slide *i'*, thereby forcing it to the left hand and closing the exhaust-passage *f'*, so that the compression in front of the piston B will commence. The same action will take place with regard to piston-slide *i* and passages *f* and *f''* during the stroke to the left of piston B, *f* being open

until edge 2 of B opens passage f'' , thereby causing piston-slides $i\ i'$ to move to the right, closing f .

Having now particularly described and ascertained the nature of our invention and in what manner the same is to be performed, we declare that what we claim is—

In an engine of the character specified, the combination, with the cylinder A, provided with inlet-ports a', a'', b, m , and m' , exhaust-ports $f\ f'$, and the exhaust-pipe g , and the hollow piston B in said cylinder, of the piston-slides $h\ h'\ i\ i'$, the air-buffer pistons $d\ d'\ d''$,

connected with said slides, and passages $f''\ f'''$ in the cylinder A, connecting the piston B with the casing of the slides $i\ i'$, substantially as shown and described, for the purpose herein set forth.

In testimony whereof we have signed our names to this specification in the presence of two subscribing witnesses.

JOHANN CARL GRÄBNER.
HENRI RUPERTI.
